[57] CLAIM

The ornamental design for hand held television set handle, as shown and described.

DESCRIPTION

FIG. 1 is a perspective view of a hand held television set handle showing my new design;

FIG. 2 is a top plan view thereof;

FIG. 3 is a right side elevational view of FIG. 2, the undisclosed opposite side being a mirror image;

FIG. 4 is a bottom plan view of FIG. 2;

FIG. 5 is a rear elevational view of FIG. 2;

FIG. 6 is a front elevational view of FIG. 2; and,

FIG. 7 is an exploded perspective view of FIG. 1.

The broken line showing of a television set is for illustrative purposes only and forms no part of the claimed design.
